UNITED STATES PATENT OFFICE

1,998,252

PACKAGE WITH CLOSED ENDS

Rodney S. Pullen, Akron, Ohio, assignor to
Pullenlite Company, Philadelphia, Pa., a corporation of Pennsylvania

Application January 19, 1932, Serial No. 587,562

10 Claims. (Cl. 206—29)

My invention relates to match packets in which the matches are ignited during their longitudinal withdrawal from the packet, stick-end foremost, the packet desirably being of the kind having 5 matches threading spaced rows of perforations of a wrap.

In this type of match packet a short flap adjacent one row of perforations folds down against the exposed match portions intermediate the 10 threaded rows and a long flap adjacent the other row of perforations folds down over the short flap, thence around the projecting match heads and up against the portion of the wrap intermediate the perforations, with the wrap fastened 15 in folded position. The portion of the packet from the stick-end row of perforations toward and beyond the match heads is herein called the match chamber portion of the packet.

A purpose of the invention is to laterally case 20 the match chamber portion of a packet of the character indicated.

A further purpose is to supply a separate wrapper for the packet surrounding the match chamber portion of the packet to close the open sides 25 of the packet and particularly the laterally open head compartment so that flashing of the flame from the packet may be prevented when the matches in it are ignited simultaneously.

A further purpose is to provide a packet of the 30 character indicated with one or more inserts to be transversely folded over the open ends (or sides) of the chamber portion of the packet preparatory to the longitudinal folding of the long flap.

A further purpose is to make the long flap of a wrap for a packet of the character indicated with lateral extensions, integral or not with the remainder of the wrap, and preparatory to the longitudinal folding of the long flap around the 40 projecting match heads, to transversely fold the extensions across the open sides of the match chamber portion of the packet with an overlapping of the extensions on to the wrap portion intermediate the rows of perforations in position to be covered by the longitudinally folded long flap.

A further purpose is to hold a wrap of the character indicated in its finished packet position by means of glue or other adhesive.

A further purpose is to stiffen a match packet 50 by lines of glue by which the material of the packet is held together.

Further purposes will appear in the specifications and in the claims.

I have elected to show one main form only of

my invention, with a few only of the modifications thereof, selecting a main form and modifications thereof that are practical and efficient in operation and which well illustrate the principles involved.

Figures 1, 2 and 3 are respectively front, right side and rear views of a finished packet embodying a desirable form of the invention.

Figure 4 is a view of a desirable form of a wrap blank of the prior art except for the strips of 10 glue.

Figure 5 is one form of insert blank for use with the wrap of Figure 4, cooperating therewith to form a combined wrap for a packet comprising a desirable embodiment of the invention.

Figure 6 is a view showing the members of Figures 4 and 5 in assembled position.

Figure 7 is a view corresponding to Figure 6 except that the cruciform wrap blank illustrated as made up of two members in Figure 6, comprises a single member in Figure 7.

Figure 8 is a third form of cruciform wrap blank in which the blank is made of three pieces instead of the single piece in Figure 7 or the two pieces in Figure 6.

Figure 9 is an insert, two of which are combined with the wrap of Figure 4 to produce the assembled cruciform of Figure 8.

Figures 10 to 14 inclusive are side views illustrating a desirable packet embodiment of the invention in successive stages of manufacture, using the form of wrap and wrap insert shown in Figures 4 and 5, respectively.

Figures 15 to 19 are front elevations of Figures 10 to 14 respectively.

Figures 20 to 24 are side views illustrating a somewhat different embodiment of the invention in successive stages of manufacture, the embodiment including the cruciform blank of Figure 7.

Figures 25 to 29 are front views of Figures 20 to 24, respectively.

Figures 30 and 31 are a plan view of a blank and a finished packet showing the application of glue stiffening to existing packets.

Figures 32 and 33 are a plan view and a finished 45 packet showing application of glue stiffening to a side-closed packet having glue stiffening and separate fastening means.

Describing in illustration and not in limitation and referring to the drawings:

The finished packet of Figures 1, 2 and 3 suitably includes in proper assembly matches 30, wrap blank 31 shown flat in Figure 4 and an insert blank 32 shown flat in Figure 5.

The wrap blank 31 of Figure 4 may be in every 55

way similar to a wrap blank of the prior art. The only difference shown in Figure 4 is in glue application affording a convenient and desirable means of stiffening the packet at the same time that the parts are held together. It is shown as provided with spaced rows of perforations 33 and 34 to receive the matches.

The perforations 34 are shown as clean-cut round holes while the perforations 33 are preferably star or petticoated perforations comprising short radial cuts that give inwardly directed petticoat flaps around the match sticks when the match sticks have been inserted through these holes.

Transverse strip coatings 35 and 36 of ignition material have been applied to the blank 31 by suitable prior operations and in such positions that, when the strip has been folded they will lie close to the perforations 34 on opposite sides of the match heads during the match withdrawals. They thus are engaged simultaneously by opposite sides of the match heads.

The wrap of Figure 4 is transversely scored at lines of folding as at 37, 38, 39, 40, 41 and 42, the short flap or match compartment front 43 of the wrap 31 comprising the portion thereof to the left of the score line 37 and the long flap comprising the portion to the right of the score line 38 and including match compartment back wall 44, outer front wall 45 and outer rear wall 46, with the end fold sections joining the walls.

Usually the short and long flaps of the wrap are turned up along the lines 38 and 39 prior to the threading of the matches into the spaced perforations 33 and 34 which then lie in line and within parallel vertical walls. This position with the matches in place is seen in Figures 10 and 15. The short flap 43 is then turned down upon the inserted matches along folded line 37 so that the inside of the flap engage with the stick ends of the matches (Figures 11 and 16). This short flap then lies parallel with the rear match chamber wall 44 between the two sets of perforations. This brings the striking material on the two flaps into opposite positions and forms the stick-enclosing portion of the match chamber. The match heads project at the left end (considered as in Figures 4 and 11) and the space including these heads forms part of what I have defined as the match chamber though in Figure 11 it is not enclosed.

In the prior construction of this packet the long flap was then folded down toward the left in Figure 4 along the fold line 40 so that the inside face of the packet front outer wall 45 engaged the outer face of the short flap 43. The remainder of the flap was then folded, first on line 41 and then on line 42 about the match heads, completing the match chamber by enclosing the heads, except that both the head portion of the chamber and the stick portion of the chamber are open at the sides.

Likewise in the prior manufacture the inner face of the rear packet wall 46 engaged the outer face of match chamber wall 44. The short fold sections 47, 48 and 49 were and are used, respectively to form the head and stick perforated end walls of the stick portion of the match chamber and to form the head end outer wall of the packet. As thus far described the packet is old and is shown in my Patent No. 1,694,864.

Attempts to close the sides of the packet have not been wholly successful, with the result that accidental flashing of all of the match heads drives flame out of the ends of the head com-

partment and burns the user. This serious condition is corrected by the present invention, because cutting off of the air from the head compartment of the packet greatly reduces the flash and the cover about the ends protects the user from injury when the flash takes place.

In accord with the present invention, closures are provided for what might be termed the open sides of the packet chamber parallel with the match sticks, closing not only the portion of the match chamber between the walls 47 and 48, but, particularly, the head portion of this chamber which lies between the end walls 47 and 49.

The closure is formed by flaps which are or may be fastened against the inside of one outer wall and fold over in position to lie beneath and will then engage the inside of the other outer wall.

The flaps or extensions shown may or may not be integral with the main wrap and, where they are not integral, may be held by fastening them directly or indirectly to the wrap. Where they are fastened to the wrap this may be done either before the wrap is supplied for folding, while it is in the machine or during the packet manufacture and as part of its formation.

In the form shown in Figure 5 an insert wrap is used separate from the wrap shown in Figure 4 and capable of attachment to the wrap of Figure 4 either way, that is, either before the wrap of Figure 4 is supplied or during the manufacture.

The separate wrap 32 is made up of a body portion 50, closure portions 51 for the sides of the match chamber of the packet and flaps 52. Glue lines 53 and 54 are shown.

In the invention shown in Figures 4, 5, and 6 it is the intention to fasten the parts together by strips of glue which may be painted upon the main wrap or insert wrap as the case may be or may be brushed upon it, affixed by rollers or applied in any other suitable way. In any case the glue may be applied to both wraps if desired.

A separate wrap is shown in position upon the main wrap and before folding of its flaps in Figures 12 and 17.

Because of convenience in the manufacture of the packet, the glue is applied to the rear face of the body 50 of Figure 5 to unite it to the inside face of the front cover 45.

In order to fasten the upper (inner) face of the body portion 50 of the insert wrap to the front wall 43 of the chamber after flap 43 has been folded upon its companion wall 44 and as both are folded upon the insert flap, glue is shown as applied to the outside face of this wall at 55 that is to the outside of the short flap 43. The flaps 52 are then folded along lines 56 and 57 upon the section 44 of the main wrap and are attached to it by strips of glue 58 shown in the drawings as applied to the outside of section 44. These flaps 52 may be fastened at their outside faces to the inside face of the rear outside wrap 46 and for this purpose the glue 54 has been shown as applied to the outside of the flaps 52. It will be obvious that in each of the glue fastenings glue can be applied alternatively to the other of the two facing surfaces instead of to that shown, or to both if preferred.

When the flaps 52 have been folded in position the parts appear as in Figures 13 and 18. In this position as will be seen the otherwise laterally open sides of the match chamber are closed including the closure of the otherwise, at this time open, match head compartment. The remainder of the long flap is then folded down about line 40

to engage the section 45 with the outer face of section 44, to bend the wrap about lines 41 and 42 so as to place in position the match head compartment end wall 49 to bring the section 46 into position against the outside 43 so that the parts of the packet appear as in Figures 14 and 19. As shown in these two figures the remainder of the match head compartment walls is provided from the main wrap. In this particular it agrees with the wrap as shown in my patent above; but that packet lacked the side closure walls and the flap or flaps by which they were held in place used a different kind of fastening means and lacked the stiffening due to glue strippings or markings across the matches. This last feature is of value whether the otherwise open sides of the match chamber be closed or not.

As compared with the packet of my patent above the packet of Figures 14 and 19 shows an extra thickness of material between each pair of parallel adjacent outside main wrap walls, the extra thickness between the pair of front main wrap walls being the body of the supplementary or auxiliary wrap and the extra thickness between the rear main wrap walls being the ends of the flaps 52 which may or may not extend in considerable distance toward each other. Alternatively they may fit inside merely enough to stay or be held in place, or fit far enough in from the sides to meet. Between these two limits of course wide variation is permissible.

Spacing of the strips or markings of glue shown in the figures gives a maximum of stiffness with a minimum quantity of glue because the parts of the adjacent wraps between the markings along with the strips of rigid fastening, are effective as miniature beams. The spacing has a further advantage in that it leaves unglued sections between glue applications, by which unglued portions of the wraps can be handled without getting glue on the applying mechanism.

From commercial considerations it would seem to be more desirable to make the flaps 52 separate from the main wraps seen in Figure 4, applying them for example in the packet forming machine in some such way as by the supplemental wraps seen in Figure 5. However, this is not essential as the wraps can be made integral with the main wraps as seen at 52' in Figure 7 and, where separately attached, can be attached in other ways of which an example is given in Figures 8 and 9. Here the flaps 52' are attached by stubs 59 for example before the main wraps reach the forming machine.

The various steps of assemblage of the parts of Figures 4 and 5 are shown in Figures 10 to 19 inclusive.

Figures 20-29 show the variation when the form of Figure 7 is used.

Starting with a position of the parts in Figure 20 corresponding with that of Figure 10 but with the flaps 52' integral with the main wrap, the short flap is folded down as in Figures 21 and 26. The flaps 52' lie in extended position and can be wrapped about the sides of the package and beneath corresponding generally to the position of Figure 18 before or after the long wrap end has been turned down against the front wall of the match chamber.

In the illustration the long end of the main wrap has been turned down in Figures 22 and 27 and the flaps 52' have not been turned beneath the match chamber until the position of Figures 23 and 28. The long part of the main flap is then turned down to form the end of the match

chamber and to the right, in counterclockwise direction, to the position shown in Figures 24 and 29.

In Figures 30 and 31 I have shown the use of transversely extending spaced bars of glue to hold a packet together independently of the means by which the lateral closure is secured. It is applied in this form to the original packet such as is shown in Figure 4 and Figures 30 and 34 may be substantially duplicates except that I have shown transverse glue stiffening across the section 45 as well as the section 46, but have omitted this stiffening material in sections 43 and 44. They differ further in the purpose of Figure 4 to receive the supplemental wrap of Figure 5 where as no supplemental wrap need be used with Figure 30 and no closure of the open lateral sides is provided in Figure 30. In other words the Figure 30 form would utilize the lateral stiffening of the glue application but would not utilize the feature collateral with this in the other figures of closing the open sides of the packet.

The packet of Figure 31 can be held together by the glue strips or can separately be held together by any suitable means, such, for example, as in my patent above, or in my patent 1,782,074.

In Figure 32 a flap 52³ corresponding generally to that of Figure 9 is secured integrally with the side of the packet and is folded in without separate fastening. The longitudinal walls of the packet are held together by a separate fastener such as bale 60 and the glue markings across the sections 45 and 46 are used for stiffening purposes only. Here again they may be applied to the other sections 43 and 44, if desired.

It will be evident that my invention provides means for transversely stiffening the packet which cooperates with a new closure for the open sides of the packet and is applicable to a variety of packets whether or not the stiffening means is used also to hold the packet together.

It will be further evident that where the stiffening means is used to hold the packet together the greatest advantage of my invention is secured.

It will be evident that the closure for the open sides acts at the same time as a bale or fastening for the entire packet, since it is united to the outer face of the back wall of the match chamber and to the inner face of the outside rear packet wall. It will independently perform this function whether or not it be fastened—as shown—to the outer face of the front wall of the match chamber or to the inner face of the front wall of the packet.

Though the bale holding function may be accomplished with any of the forms shown in which there is a closure which is fastened to the rear wall of the packet, the bale idea will be clearer from those forms in which a supplemental wrap in fact transversely surrounds the match chamber.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. A packet of the character indicated and comprising a wrap having spaced rows of perfora- 75

- tions threaded by the matches and the wrap folded longitudinally of the matches from the stick end perforations around the match heads and up to form a packet back in combination with 5 a paper insert closing the sides of the match chamber formed by the folding of the wrap and covering the match heads.
2. A packet of the character indicated and comprising a wrap having spaced rows of perforations threaded by the matches and the wrap folded longitudinally of the matches from the stick end 10 perforations around the match heads and up to form a packet back in combination with paper inserts, one at each side of the match chamber 15 formed by the folding of the wrap, and each insert having an intermediate portion closing one of the sides and having opposite edges covered respectively by the front fold and the back fold of the wrap.
- 20 3. A wrap blank having spaced rows of perforations, matches threading the corresponding perforations of the spaced rows, a short flap turned down upon the matches, an insert extending transversely across the turned down short flap 25 and folded downwardly across the match chamber and inwardly at the back of the chamber to overlap upon the wrap portion intermediate the rows of perforations, and a long flap of the blank folded down upon the insert around the head 30 ends of the matches and upon the overlapping portions of the insert to back the packet.
4. A cruciform blank having spaced rows of perforations, matches threading the corresponding perforations of the spaced rows, a short flap turned down upon the matches, a long flap having the lateral extensions that form the cross portion of the blank turned down upon the short flap, the lateral extensions folded down across the sides of the packet and up upon the wrapped 35 portion intermediate the spaced rows and the long flap folded around the head ends of the matches and up upon the overlapping portions of lateral extensions.
5. In a match packet, a blank having two sets 40 of spaced openings, matches extending through the openings with their heads adjacent one set of openings, the blank being folded to form a match-head compartment and a separate match-striking compartment, both of which compartments have double front and rear walls, flaps secured to the 45 wrap extending over the sides of the match-head and match-striking compartments and entering between the double walls and striking material on the inside of the match-striking compartment.
- 50 6. A match packet comprising a wrap folded to form compartment walls providing compartments for dividing off the heads of matches from the sticks of the matches, the heads of the matches being in one compartment and the sticks beyond the match head being located in a second 55 compartment, ignition material upon the walls of the second compartment, the second compartment providing a striking compartment in which the matches are ignited upon withdrawal, and outer walls and closures for the sides of the packet 60 separate from the wrap extending inwardly from the side edges of the assembled packet about the
- packet and between the walls thereof and glued to one of the outer walls to hold the walls of the packet together and at the same time allow for withdrawal of the matches from the packet.
7. A packet that includes a wrap having parallel relatively spaced transverse rows of perforations, matches threading the perforations with the match heads adjacent the perforations of one row and the match stick ends projecting out of the perforations of the other row, and the wrap 10 folded longitudinally of the matches about the match portions intermediate the said rows, from the head end perforations down about the match portions intermediate the rows and from the stick end perforations down upon the first folded 15 portion of the wrap, around the match heads and against the wrap portion between the said rows, closures for the sides of the packet, united to the front and back walls, striking material on the inside walls of the packet, there being two 20 thicknesses of wrap material on the front and two thicknesses of wrap material on the back of the packet and glue uniting the two thicknesses of wrap material at the front and also at the back, whereby the front and rear walls are stiffened.
8. A match packet comprising a row of matches, a wrap wound around the row of matches continuously in one direction, longitudinally of the matches, across them, longitudinally 25 of them, across them, longitudinally of them, across them, and longitudinally of them, so that the front and back of the packet each have two thicknesses of wrap material, striking material on the inside of the front and back walls and glue between the two thicknesses of wrap material at the front and back of the wrap to stiffen the front and back walls.
9. A match packet comprising a row of matches, a wrap wound around the row of matches continuously in one direction, longitudinally 30 of the matches, across them, longitudinally of them, across them, longitudinally of them, across them, and longitudinally of them, so that the front and back of the packet each have two thicknesses of wrap material, striking material on the inside of the front and back walls, sides folded over and extending between the two thicknesses of wrap material at one wall of the packet 35 and glue between the two thicknesses of wrap material at the front and back of the wrap to secure the sides and to stiffen the front and back walls.
10. A match packet comprising a row of matches, a wrap wound around the row of matches continuously in one direction, longitudinally 40 of the matches, across them, longitudinally of them, across them, longitudinally of them, so that the front and back of the packet each have two thicknesses of wrap material, striking material on the inside of the front and back walls, sides folded over and extending between the two thicknesses of wrap material at one wall of the packet 45 and glue between the two thicknesses of wrap material at the front and back of the wrap to secure the sides and to stiffen the front and back walls.

RODNEY S. PULLEN.
